UNITED STATES PATENT OFFICE

CHARLES C. SPREEN, OF DETROIT, MICHIGAN, ASSIGNOR TO KELVINATOR CORPORATION, OF DETROIT, MICHIGAN, A CORPORATION OF MICHIGAN

MECHANICAL REFRIGERATION

Application filed August 6, 1926. Serial No. 127,530.

My invention relates to mechanical refrigeration, and particularly to unitary fluid-coolers, and the principal object of my invention is to provide a new and improved 5 fluid-cooler of this type. In the drawings accompanying this specification and forming a part of this application I have shown, for purposes of illustration, one form which my invention may assume. In these drawings:

Figure 1 is a front elevation of this illustrative embodiment of my invention,

Figure 2 is a vertical section parallel to the front of the fluid-cooler taken on the line 15 2—2 of Figures 3 and 4,

Figure 3 is a horizontal section taken just within the top of the fluid-cooler on the line 3—3 of Figure 2, while

Figure 4 is a second horizontal section 20 taken on the line 4—4 of Figure 2.

The embodiment of my invention herein shown comprises a cabinet 11 provided with side walls 12 and a rear wall 13 and a front wall 14 permanently assembled together, and 25 with a horizontal partition wall 15 permanently assembled with the side walls 12 and rear wall 13 and front wall 14 and dividing the cabinet 11 into an upper refrigerating compartment 16 and a lower mechanism compartment 17.

Projecting inwardly from the side walls 12 are a pair of cleats 18 supporting a base 19 removably secured to the cleats 18 by means of bolts 20 and itself supporting a compressor 21 provided with an intake duct 22 and an outlet duct 23, an electric motor 24 operating the compressor 21 by means of a belt 25, and a condenser 26 provided with an inlet end 27 connected to the outlet duct 23 of the compressor 21, and with an outlet end 28 connected to a condensed refrigerant supply duct 29.

Mounted within the refrigerating compartment 16 is a brine tank 30 arranged to contain a non-congealing fluid, such as brine, and positioned within this brine tank 30 immersed in the brine contained therein is a refrigerant expansion coil 31 having its inlet end connected through an expansion valve 32 to a condensed refrigerant supply duct 33

detachably connected at 34 to the condensed refrigerant supply duct 29, and its outlet connected to an expanded refrigerant return duct 35 connected by means of a connection 36 to the inlet duct 22 leading to the compressor 21.

Also positioned within the brine tank 30 are a pair of fluid-cooling coils 37 each having its inlet 38 connected to a fluid supply duct 39 and its outlet 40 connected to a cooled fluid delivery duct 41 projecting through the front wall 14 of the cabinet 11 and leading to a drinking fountain 43 through a suitable control valve 44 and to a delivery orifice 45 through a second suitable control valve 46.

The cabinet 11 is also provided with a suitable cover 47 arranged to close the upper end of the cabinet 11, and therefore the upper end of the refrigerating compartment 16, and provided with a projection 48 arranged to simultaneously close the upper end of the brine tank 30; the drinking fountain 43 is provided with a suitable waste duct 49 extending through the front wall 14 of the cabinet 11 and the mechanism chamber 17 and the wall 13 of the cabinet 11 to connect with a suitable waste connection provided at that point; this waste duct 49 is provided with a branch 50 terminating in a cup 51 positioned below the orifice 45 to receive fluid flowing or dripping from the orifice 45; and this waste duct 49 is provided with a second branch 52 extending upwardly through the partition 15 into the brine tank 30 and terminating in the brine tank 30 at the level at which the brine is to be maintained therein.

In addition, there is provided within the mechanism chamber 17 a thermostat 53 controlling the action of the motor 24 in the usual manner and having its expandible chamber connected by means of a duct 54 to a bulb 55 located within the brine in the brine tank 30 and accordingly operative to cause operation or rest of the motor 24 and compressor 21 according to the temperature of the brine within the brine tank 30.

From the above description it will be obvious to those skilled in the art that I have provided a new and improved unitary water-cooler. At the same time it will also be ob-

vious to those skilled in the art that the particular embodiment of my invention herein shown and described may be variously changed and modified without departing 5 from the spirit of my invention or sacrificing the advantages thereof, and it will therefore be understood that the disclosure herein is illustrative only and that my invention is not limited thereto.

10 I claim:

1. A unitary fluid-cooler comprising: a cabinet provided with a partition dividing the interior of said cabinet into a lower mechanism compartment and an upper refrigerating compartment, a brine tank within said refrigerating compartment, a fluid-cooling device within said brine tank, a cooled-fluid delivery duct connected to said fluid-cooling device, a refrigerant expansion device also within said brine tank and disposed in a region thereof remote from the fluid cooling device, refrigerant compressing mechanism within said mechanism compartment, and connections operatively connecting said mechanism and said refrigerant expansion device. 20

2. A unitary fluid-cooler comprising: a cabinet provided with a partition dividing the interior of said cabinet into a mechanism compartment and into a refrigerating compartment open at the top, a brine tank within said refrigerating compartment also open at the top, a single removable cover closing both the top of said refrigerating compartment 30 and the top of said brine tank, a fluid-cooling device within said brine tank, a cooled-fluid delivery duct connected to said fluid-cooling device, a refrigerant expansion device also within said brine tank, refrigerant compressing mechanism within said mechanism compartment, and connections operatively connecting said mechanism and said refrigerant expansion device. 40

3. A unitary fluid-cooler comprising: a cabinet provided with a partition dividing the interior of said cabinet into a lower mechanism compartment and into an upper refrigerating compartment open at the top, a brine tank within said refrigerating compartment also open at the top, a single removable cover closing the top of said refrigerating compartment and the top of said brine tank, a fluid-cooling device within said brine tank, a cooled-fluid delivery duct connected to said 50 fluid-cooling device, a refrigerant expansion device also within said brine tank, refrigerant compressing mechanism within said mechanism compartment, and connections operatively connecting said mechanism and said refrigerating expansion device. 60

4. A unitary fluid cooler comprising a cabinet having a brine tank located therein, a fluid cooling device within said brine tank, a refrigerant expansion device also within said 65 brine tank, said fluid cooling device and re-

frigerant expansion device being disposed remotely from each other in the interior of said tank, and means for supplying and exhausting refrigerant liquid and water from the refrigerant expansion device and fluid cooling device respectively. 70

In testimony whereof I hereunto affix my signature.

CHARLES C. SPREEN.
